UNITED STATES PATENT OFFICE.

JAMES DONNELLY, OF PHILADELPHIA, PENNSYLVANIA.

ELECTRIC STOP MOTION FOR LOOMS.

Application filed July 22, 1926. Serial No. 124,165.

My invention relates to electrically controlled stop motions for looms which employ a series of heddle frames for forming the shed in the manufacture of fabrics.

5 The details of my invention will be fully disclosed hereinafter, reference being had to the accompanying drawings, of which:

10 Fig. 1 illustrates diagrammatically one of the heddle frames of a loom and its supporting mechanism having my improved stop motion control associated therewith;

15 Fig. 2 is a front elevation of my control unit drawn on an enlarged scale; and

20 Fig. 3 is a sectional elevation taken along 15 the line 3—3 of Fig. 2.

Referring to Fig. 1, one of the heddle frames is illustrated at 1. Thread eyes 2 are suitably secured in the frame 1 for receiving the warp threads of the fabric being woven.

25 The frame 1 is supported by means of straps 3, 3 which pass around suitable pulley wheels 4, 4 rotatably mounted on the frame of the loom (not shown). An oscillating lever 5 is pivotally attached to loom frame at 30 6. One of the straps 3 is attached to the lower end of the lever 5 at 7, and the other strap 3 being attached to the upper forked end of the lever 5 at 8.

The upper end 8 of the lever 5 is also connected by means of a wire 9 to one arm 10 of 35 a bell-crank lever or jack 11, pivoted at 12 to the loom frame. The other arm 13 of the bell-crank lever 11 is connected by a wire 14 to one end of a strap 15 which passes around 40 a pulley 16 rotatably mounted on the loom frame. The opposite end of the strap 15 is connected by means of a wire 17 to one end of a strap 18 which passes around a pulley 19, rotatably mounted on the loom frame.

45 The other end of the strap 18 is connected to the centre of a bow wire 20, the ends of which are attached to the lower side of the frame 1, adjacent each end thereof.

The mechanism just described is common 50 to looms adapted to weave fabrics of great variety as to texture and design. Some looms are provided with as many as twenty-five heddle frames of the form above described placed in the loom frame side by side

55 or parallel to each other and each heddle frame is provided with a supporting harness of the form above described.

The different heddle frames are relatively raised and lowered by suitable design forming mechanism to form the shed and pattern of the fabric, said mechanism being con-

nected to the jack 11 in any suitable manner. It will be noted that by oscillating the jack 11, the heddle frame will be raised and lowered.

60

To form a perfect shed, the harness above describe must be held taut in order to raise and lower the heddle frame in a substantially horizontal plane. Should the harness become slack at any point the result would be a heddle frame raised higher on one edge than on the other, permitting the warp threads at the low side to remain in the path of the shuttle which carries the weft threads through the open warp shed, resulting in broken warp threads or ends referred to in the trade as "smashes".

65

Slackness of the harness will also cause loose woven fabric and fabric having some of the warp threads floating on the under side of the fabric due to the fact that they were not raised to a proper level to be woven into the fabric. This condition may exist for a considerable length of time and the weaver would not be aware of the fact.

70

The principal object of my invention is to prevent such conditions by automatically stopping the loom immediately upon the harness of any one of the heddle frames becoming slack, which may be caused by a broken or strained supporting strap or wire or any one of a number of different causes well known in the art of weaving.

75

To attain this object I provide an inverted U-shaped frame 25 which bridges the series of parallel wires 17. The legs 26 of the bridge frame 25 are grooved at 27 to receive the ends 28, 28 of an adjustable frame 29 having upper and lower rails 30 and 31 connecting the end rails 28, 28. Adjusting bolts 32, 32 pass through the bridge beam 25, and are adapted to threaded openings 33, 33 in the upper rail 30 of the adjustable frame 29.

80

A series of contact needles 35, 35 are vertically and slidably mounted in the upper and lower rails 30 and 31 of the frame 29. Each contact needle 35 is provided, intermediate said rails, with a block 36 having an aperture 37 passing therethrough.

85

For each heddle frame 1 in use in the loom, the number of which may vary according to the fabric being woven, the associated wire 17 passes through the aperture 37 of the respective needle and supports the needle substantially in the position shown at A, Fig. 2, while those not in use are maintained

90

95

100

105

110

in the position B, Fig. 2, by means of set screws 38 tapped into the upper rail 30 and adapted to engage the inoperative needles 35 as shown, lock nuts 39 being provided to prevent the loosening of the set screws 38 by vibration of the loom. A limit bar 40 for the upward movement of the needles is mounted on the adjusting screws 32, see Figs. 2 and 3.

10 Each needle 35 is provided with a spring 41 intermediate the upper side of the block 36 and lower side of the upper rail 30 of the frame 29.

Under normal operating conditions and 15 when the supporting harness of the heddle frames 1, 1 are taut the wire 17 of each thereof supports the corresponding needle 35 in the A position shown in Fig. 2, however, should the harness become slack, due 20 to a broken or strained strap or wire or some other reason, the wire 17 will become slack, permitting the needle 35 associated therewith to move downward under the influence of its spring 41 until the point 42 of the 25 needle engages a contact 43 which is adjustably mounted in a conductor bar 44.

The conductor bar 44 is secured at each of its ends in a head 45 slidably mounted in a slot 46 formed in each leg 26 of the bridge frame 25. Insulating bushings and washers 47 and 48, prevent electrical contact between the bar 44 and each head 45. Each head 45 is provided with a lug 49 adapted to receive the head 50 of a bolt 51 which passes 30 through a lug 52 on each leg 26, by means of which the conductor bar 44 may be vertically adjusted relative to the points 42 of the needles 35 which are adjusted relative to the normal position of the wires 17 by 35 adjusting the frame 29, a nut 53 being provided on each bolt 51 and adapted to engage the upper side of each lug 52.

Set screws and lock nuts 54 and 55 respectively maintain the contacts 43 in position within the conductor bar 44.

As shown in Fig. 1, a source of electrical energy is illustrated at 56 and is connected in series with the coil 57 of the electro-magnetic trip mechanism of the loom by means 50 of which mechanism, forming no part of my invention, is set in motion to stop the loom when the electro-magnetic trip mechanism is energized. A conductor 58 connects one side of the source of energy 56 with the bridge frame 25 and a second conductor connects the conductor bar 44 with the other side of said source of energy through the coil 57 of the said trip mechanism.

Should any one of the heddle frame harnesses become slack, its associated wire 17 will likewise become slack permitting the point 42 of the contact needle 35 to drop into contact with the corresponding contact 43 on the bar 44 thereby completing the electrical circuit which passes from the

source of energy 56, conductor 58, bridge frame 25, adjustable frame 29, needle 35, contact 43, conductor bar 44, conductor 59, coil 57, conductor 60 and back to the opposite side of said source of energy, thereby 70 causing the electro-magnetic trip mechanism 57 to function and thereby stop the loom immediately upon the occurrence of slack in the harness.

Having fully described one preferred 75 form of mechanism for attaining the object of my invention, modifications and equivalents thereof will obviously present themselves to one mechanically trained, therefore, only such limitations should be placed 80 upon the scope of my invention as are prescribed in the appended claims, or dictated by the prior art of record.

I claim:

1. In combination with a loom employing 85 heddle frames, a normally taut harness for operating each of said heddle frames and an electrical stop motion for said loom, each harness including a horizontally extending element; an independent normally open switch 90 for each harness having a fixed contact and a movable contact, said movable contact being operatively associated with the horizontal element of said harness, said movable contact being adapted to engage said fixed contact when the harness becomes slack; a frame 95 bridging said horizontal element for supporting said contacts; means for insulating one of said contacts from said frame; a frame for supporting said movable elements 100 in said bridge frame; means for adjusting said supporting frame relative to the normal operating plane of said horizontal element and means for adjusting said fixed contact relative to said movable contact. 105

2. In combination with a loom employing heddle frames, a normally taut harness for operating each of said heddle frames and an electrical stop motion for said loom, a 110 normally open switch for said stop motion comprising a bridge frame; a conductor bar mounted in and insulated from said bridge frame; a supporting frame mounted in said bridge frame; fixed contacts on said conductor bar; relatively movable contacts 115 slidably mounted on said supporting frame each movable contact engaging a normally taut element of said harness; and a spring on each of said movable contacts for effecting the closing of said switch when said normally taut element becomes slack. 120

3. In combination with a loom employing heddle frames, a normally taut harness for operating each of said heddle frames and an electrical stop motion for said loom, a normally open switch for said stop motion comprising a bridge frame; a conductor bar mounted in and insulated from said bridge frame; a supporting frame mounted in said bridge frame; fixed contacts on said con- 125 130

ductor bar; relatively movable contacts 5 slidably mounted on said supporting frame each movable contact engaging a normally taut element of said harness; and a spring on each of said movable contacts for effecting the closing of said switch when said normally taut element becomes slack; a limit stop for said movable contacts; and means for selectively maintaining said movable contacts in their open positions.

4. In combination with a loom employing heddle frames, a normally taut harness for operating each of said heddle frames and an electrical stop motion for said loom, a 15 normally open switch for said stop motion comprising a bridge frame; a conductor bar mounted in and insulated from said bridge frame; a supporting frame mounted in said bridge frame; fixed contacts on said conductor bar; relatively movable contacts 20 slidably mounted on said supporting frame each movable contact engaging a normally taut element of said harness; and a spring on each of said movable contacts for effecting the closing of said switch when said normally taut element becomes slack; means 25 for adjusting the position of the supporting frame relative to the bridge frame; and means for selectively maintaining said movable contacts in their open positions.

frame relative to the bridge frame; and means for adjusting the position of the conductor bar relative to the bridge frame. 30

5. In combination with a loom employing heddle frames, a normally taut harness for operating each of said heddle frames and an electrical stop motion for said loom, a normally open switch for said stop motion 35 comprising a bridge frame; a conductor bar mounted in and insulated from said bridge frame; a supporting frame mounted in said bridge frame; fixed contacts on said conductor bar; relatively movable contacts 40 slidably mounted on said supporting frame each movable contact engaging a normally taut element of said harness; a spring on each of said movable contacts for effecting the closing of said switch when said normally taut element becomes slack; means 45 for adjusting the position of the supporting frame relative to the bridge frame; means for adjusting the position of the conductor bar relative to the bridge frame; and means 50 for adjusting the fixed contacts on said conductor bar relative to the movable contacts on said supporting frame.

JAMES DONNELLY.
